ISIDORE DITESHEIM, OF CHAUX-DE-FONDS, SWITZERLAND, ASSIGNOR TO THE FIRM OF
FABRIQUE MOVADO L. A. J. DITESHEIM & FRÈRE.

BRACELET-WATCH.

1,142,554.

Specification of Letters Patent.

Patented June 8, 1915.

Application filed May 6, 1913. Serial No. 765,807.

To all whom it may concern:

Be it known that I, ISIDORE DITESHEIM, a citizen of the Swiss Republic, and resident of Chaux-de-Fonds, Switzerland, have invented a new and useful Bracelet-Watch, of which the following is a full, clear, and exact specification.

Bracelet watches have been already made with an elongated case containing the watch movement and having an inner surface curved in the direction of the curve of the bracelet in order to adapt itself more or less perfectly to the form of the arm. But in bracelet watches of this kind as hitherto constructed, the watch movement or motion work retained the usual round form of watch mechanisms, that is to say, it was mounted upon a large circular pillar plate, so that the movement or motion work could only occupy a greatly reduced portion of the free space of the case.

In the object of augmenting the curvature of the case of a bracelet watch of this kind, so that it may conform exactly to the shape of the human arm, and of enabling at the same time to obtain a better use of the free space contained in the case that is to say, of enabling the maker to place in a case of predetermined dimensions a larger watch movement or motion work and consequently a motion work or movement of better going capacity or of being able to place a movement or motion work of predetermined dimensions in a smaller case, the applicant has had the idea of mounting the movement or motion work upon a pillar plate bent angularly according to the form of several faces of a prism and extending throughout all the available space in the interior of the elongated case. For instance, the pillar plate may possess two elbows and have a middle part bearing the axles of all the wheels of the movement or motion work except that of the balance wheel and two end parts sloping with regard to this middle part and of which the one bears the greater part of the organs serving for winding up the barrel spring and for hand-setting, while the other part supports the axle of the balance wheel and its accessories, the fork of the escapement being bent angularly in order to compensate the difference in level between the escapement wheel and the corresponding organs of the axle of the balance wheel.

The invention is illustrated by way of example in the accompanying drawing as follows.

Figures 1 and 2 show in side elevation and in plan view a bracelet watch of this kind attached to an arm (supposed to be sectioned in Fig. 1). Fig. 3 shows a plan view of the movement or motion work of the watch, and Fig. 4 shows a longitudinal section of the case containing the said movement or motion work.

As may be seen in these figures the bracelet watch comprises an elongated case A provided at its two opposed ends with links or handles 9 connected to flexible bands 10 which are secured together by a buckle 11 and a strap or strip 12. The lower face of this case A, that is to say the face, which is opposite to the dial a is curved in conformity with the shape of the arm, while the said dial is protected as well as the hands b, c moving in front of it, by means of an elongated glass d.

The pillar plate B of the motion work or movement is formed of a flat plate, angularly bent according to two obtuse angles. Its middle portion e placed between the two end portions i, j, which are at an angle with regard to the middle one, supports between it and a pentagonal parallel plate J, the axle of the central wheel D, the pinion of which f engages with the wheel E of the going barrel C, also placed between B and J. The axle g of the going barrel C bears beneath the pillar plate, the winding wheel G engaging with an intermediate wheel H maintained under the end part i of the pillar plate B parallel to the said part i, by a washer held by two screws and engaging normally with the winding pinion I placed upon the winding stem L. The planes of the tooth wheels G and H intersect one another at an obtuse angle. Under the middle part e of the pillar plate B there is articulated the click k of the winding mechanism, on which there acts a spring l also placed beneath the middle part e of B.

Above the plate J, the axle of the central wheel D bears a pinion m connected by the intermediate wheels n, o, supported upon J parallel to the part e of B, with a wheel K in one piece with a pinion p and held together with this latter parallel to the end part i of the plate upon a support M adapted to the said part i, perpendicularly to this

latter. The winding stem I is guided on the one hand in this support M and on the other hand in a part N adapted to the part i of the plate B. It terminates in a knob 15 placed in a recess C of the case A. Upon a quadrangular part of this stem I is placed a sliding double pinion of Breguet P, which can engage alternatively with the pinion of the winding stem I or with the pinion p according as the stem I is in the position corresponding to the winding up of the barrel spring or in that corresponding to the hand setting. Normally, the pinion P engages with the pinion of the stem I as is shown in the drawing. If it is desired to bring it into the position which corresponds to the hand setting, it is sufficient to draw the winding stem in the direction of the arrow α so as to act by its annular groove q upon the piece r which is articulated upon the part i of B and is under the influence of a spring s also adapted to i and acts by means of an arm t upon a rocking lever u pivoted upon the part i of B, subjected to the action of a spring w adjusted to the same part i and penetrating into the groove v of the sliding pinion P. The hand setting having been effected, the pinion P can be brought back into the position corresponding to the winding by pushing the stem I in the opposite direction to the arrow α .

It will be seen from the preceding that the greater part of the organs which serve for the winding up of the barrel spring and for the hand setting are supported by the end part i of the plate B. The central wheel D transmits when the watch is going, its motion by means of the pinion and of the wheel 1, 2, of the wheel and the pinion 3, 4 and of the pinion 5 of the escapement wheel to the escapement wheel 6, the axles of these three sets of wheels and pinions being held between the middle portion e of the pillar plate B and a second small plate U of generally triangular form with a lateral recess 16, adapted to the plate B and parallel to this latter. The anchor V operating with the escapement wheel 6 is held between the middle part e of the pillar plate B and a small curved bridge 7 screwed to the plate B and prolonged by an elbow fork 8 co-operating with organs of the axle of the balance wheel 14, held between the sloping end part j of the plate B and a cock y screwed to the said part j and parallel to it, the said balance wheel being combined as usual with its ordinary accessories (hair spring etc.).

It will be seen by the preceding that the axle of the balance wheel is mounted upon the part j of the pillar plate B and makes an acute angle with the axles of the other moving parts of the movement or motion

work supported by the middle portion e of the said plate. It will be understood that with this arrangement almost the entire internal space of the case is utilized for containing the movement and that a case of given dimensions which could for instance contain an ordinary circular movement of 8 lines, would be able to contain a movement of the described caliber, of which the organs would possess the dimensions of the organs of the usual circular movement of 11 lines. Consequently, the watch, of which the case is provided with such a movement will go much more precisely and will support much longer use. The bracelet watch described can be constructed only with an hour hand and with an hour hand and with a minute hand as it is shown in Fig. 4.

What I claim is:

1. In a bracelet-watch having a case of elongated shape with a lower surface curved to correspond with the curvature of a human arm, a pillar plate of elongated shape, bent angularly according to the form of several adjacent plane faces of an obtuse angled prism and extending across the whole of the available interior space of the said case, and a watch movement mounted upon and distributed over all the faces of the said pillar plate, across the whole of the said elongated case, in order that a better use of the interior space of the case may be obtained for containing the movement, substantially as described.

2. In a bracelet-watch having a case of elongated shape with a lower surface curved to correspond with the curvature of a human arm, a pillar plate twice bent angularly according to the form of three adjacent plane faces of an obtuse angled prism and extending across the whole of the available interior space of the said case, a watch movement mounted upon and distributed over all three faces of the said pillar plate, across the whole of the said elongated case and having its balance wheel supported on one end part of the said pillar plate, its winding stem on the other end portion of the said pillar plate and its escapement wheel on the middle portion of the said pillar plate, and an escapement fork bent angularly in order to compensate the angular difference of the planes of the escapement wheel and of the balance wheel, substantially as described.

In witness whereof I have hereunto signed my name this 22nd day of April 1913, in the presence of two subscribing witnesses.

ISIDORE DITESHEIM.
